UNITED STATES PATENT OFFICE

2,606,643

AUGER TYPE ELEVATOR

Eldon G. Tidwell, Cherokee, Okla.

Application July 22, 1949, Serial No. 106,271

3 Claims. (Cl. 198—9)

1

This invention relates to auger type elevators adapted for moving and/or elevating grain or other loose materials from one location to another as from a pile into a truck, bin or other place of higher elevation, the principal objects being to provide an elevator of this character that is readily adapted to any given elevating job; to provide an auger type elevator with a portable transport that forms a unitary part thereof and which carries the prime mover for actuating the auger; to provide an elevator that is readily adjusted to different angles of elevation; to provide an elevator of the auger type that is readily adjusted to length by addition of extra joints of tubing and auger sections; to provide a connection for an auger extension that is adapted to be projected into a pile of material at various angles from the inlet head or boot of the elevator for effecting movement of material thereto; to provide an elevator that is readily adapted for transport from one place to another; and to provide an adjustable inlet head or boot.

Other objects of the invention are to provide an auger type elevator that is efficient in operation and capable of handling large quantities of material.

In accomplishing these and other objects of the invention, I have provided improved structure, the preferred form of which is illustrated in the accompanying drawings wherein:

Fig. 1 is a side elevational view of an auger type elevator showing elevation of material from a pile into a truck bed.

Fig. 2 is a similar view showing the elevator adjusted to a higher discharge level to elevate, for example, grain from a pile into a granary.

Fig. 3 is a detail side elevational view of the auger extension which is adapted to gather material from a pile and move it to the elevator boot.

Fig. 4 is an enlarged perspective view showing the mounting of the motor and winding drum for changing the elevation.

Fig. 5 is a perspective view particularly illustrating the roller and guide track used in changing elevation of the elevator.

Fig. 6 is a perspective view of the boot end of the elevator particularly illustrating the mounting of the driving connection for the auger.

Fig. 7 is a horizontal section through the drive casing, particularly illustrating the universal joint for mounting the extension auger illustrated in Fig. 3.

Referring more in detail to the drawings:

2

1 designates an elevator constructed in accordance with the present invention and which includes a tubular casing 2 formed of sections 3 and 4 having flanged ends 5 and 6 which are adapted to be connected together by suitable fastening devices such as bolts 7 so as to permit insertion of additional tubular sections if a longer elevator is desired. The outer end of the section 3 carries a flange 8 to which is attached a discharge spout 9 that is secured by fastening devices such as bolts 10. Mounted within the tubular casing is an auger conveyor 11 which may be composed of interconnected shaft sections 12 having flights 13 substantially filling the tubular casing to effect elevation of material from the end 14 of the section 4 to the spout end of the section 3 when the auger is rotated therein. The inlet end of the tubular casing is provided with band-like clamps 15 and 16 that encircle the casing and which have ears 17 and 18 secured together by fastening devices such as bolts 19 by which the bands may be contracted about the tubular casing as best shown in Fig. 6.

25 Fixed to and extending longitudinally of the bands 15 and 16 are rods 20 and 21 that are spaced outwardly from the casing and which have laterally turned ends 22 and 23 which are secured to a transmission housing 24 as indicated at 25. The housing 24 comprises complementary pan-like sections 26 and 27 having substantially flat sides 28 and 29 provided with abutting marginal walls 30 and 31 that are secured together by fastening devices 32 that extend through lateral flanges 33 and 34 of the walls 30 and 31, a suitable gasket 35 being inserted between the flanges to provide a lubricant-tight inner compartment 36. Located in the side portions 27 and 28 of the housing sections are bearing bosses 37 and 38 having recesses 39 and 40 mounting antifriction bearings 41 and 42 to journal the end of the auger shaft 12. The auger shaft projects through the bearing boss 38 and has a reduced end for mounting a universal joint 43 that is adapted to be connected with an auger 44 as best shown in Fig. 3. The auger section 44 includes a shaft 45 similar to the shaft 12 and is provided with a flight 46 by which grain is moved toward the inlet or boot end of the elevator.

Provided on the side portion 27 of the housing at the end opposite the bearing bosses 37 is a bearing boss 47 that is adapted to contain an antifriction bearing 48 journaling one end of a shaft 55 49, the opposite end of which is journalled in

3

a bearing 50 that is mounted on a bracket 51 that projects from the side of the tubular casing section 4, as best shown in Fig. 6. The shaft 49 projects into the compartment 36 and mounts a sprocket 52. Operating over the sprocket 52 and over a sprocket 53 on the shaft 12 is a chain 54 whereby the main conveyor shaft 12 is adapted to be operated from the shaft 49 as later described.

Slidable on the end of the tubular section and within the space under the rods 20 and 21 is a sleeve 55 that is adapted to be moved to and from the chain housing to vary the size of the inlet, the sleeve being manipulated by a rod 56 that is fixed to the sleeve and slidably mounted in a bearing 57 on the band 15. The free end of the rod terminates in a lateral end 58 to facilitate manipulation thereof.

The tubular casing thus described is mounted on a truck 59 which includes a frame 60 having angle members 61 and 62 spaced apart at their rear ends and which converge forwardly under the tubular casing to connect therewith by brackets 63 as best shown in Figs. 1 and 2. The rear ends of the angle members are connected by a cross bar 64, on the ends of which are journalled ground wheels 65 and 66. Supported on the cross bar 64 and extending upwardly therefrom near the mid portion is a post 67 having a yoke-shaped seat 68 to seat the tubular housing. When the device is to be transported, the tubular casing is retained in the seat by a clamp 69 that extends across the top thereof and has its ends secured to the seat by fastening devices such as bolts 70, however, when it is necessary to raise the tubular housing to a higher position, the retaining clamp is removed as shown in Fig. 2.

Pivotedly connected with the ends of the cross member 64 are upwardly and rearwardly diverging angle members 71 and 72 which are interconnected at their converging ends by a spool-like roller 73 that is journalled on a cross shaft 74 mounted in ears 75 carried by the ends of the members 71 and 72. Fixed to the underside of the tubular housing section 3 is a channel-shaped rail 76 that engages between the flanges 77 and 78 of the spool-shaped roller as best shown in Fig. 5. The members 71 and 72 constitute a prop that is adapted to be raised and lowered on its pivotal connection with the cross bar 64 to effect raising and lowering of the discharge end of the tubular housing as will be clearly apparent by inspection of Figs. 1 and 2.

In order to raise and lower the prop, the members 71 and 72 are interconnected by a shaft 79 mounting a pulley 80. Operating over the pulley 80 is a cable 81 having one end attached to the forward end of the track 76 by a hook-like bracket 82. The other end of the cable extends forwardly and is wound on a winding drum 83 that is pivotally rotatable on a shaft 84 suspended by arms 85 and 86 from a clamping band 87 that encircles the tubular housing section 4. The shaft 84 includes a crank 88 on one end having a handle 89 by which the drum may be rotated to wind the cable thereon. Winding of the cable on the drum raises the gin pole and causes the spool-like roller 73 to run on the track 76 and raise the tubular housing, for example, from the position shown in Fig. 1 to the position shown in Fig. 2. When the tubular housing is in desired elevation, the handle 89 of the crank is engaged with the hook 90 to retain the tubular housing in adjusted position.

Mounted on the rear ends of the angle members 75 adaptable to various positions in which it may

4

60 forwardly of the cross bar 64 are rods 91 and 92 mounting a motor unit such as an internal combustion engine 93, the engine having a power shaft 94 mounting a pulley 95. Carried on a bracket 96 that is attached to the bars 91 and 92 laterally of the motor shaft is a post 97 carrying a bearing 98 mounting the rear end of a countershaft 99. Fixed to the countershaft on the rearwardly projecting end thereof is a pulley 100 that is adapted to be driven by the motor pulley 95 through a belt 101. The forward end of the shaft is journalled in a bracket-like post 102 that is also carried between the member 60 and which mounts a bearing 103 through which the shaft extends. The forward end of the shaft is connected with the shaft 49 by a universal joint 104 to allow for change in angularity between the respective shafts upon angular adjustment of the tubular housing of the elevator.

20 Assuming that the elevator is constructed and assembled as described, it is adapted for ready transport to any location where it may be used for lifting grain, for example, from a pile into a truck bed as shown in Fig. 1. For this use, the tubular housing may remain in the seat 70 as the elevator can tilt on the wheels 59 to allow proper elevation of the discharge end over the bed of a truck as shown in Fig. 1. When the motor is in operation the pulley thereof operates the belt 95 and pulley 97 to turn the shaft 99 and operate the shaft 49 through the universal joint 104 to drive the sprocket 52. The sprocket 52 drives the sprocket 53 through the chain 54 to turn the main conveyor shaft 12 and cause rotation of the auger within the tubular housing. With the adjusting sleeve 55 retracted and the exposed end of the auger resting upon the pile of material, the material is moved into the open end of the tubular housing and upwardly therethrough for discharge through the support 9 into the bed of the truck.

If the material is to be moved to a higher elevation as, for example, into a grain bin as shown in Fig. 2, the fastening devices 7 are removed and the crank handle 88 is disengaged from the hook 90. The winding drum is then rotated by the crank 88 to wind up the cable and effect upward and forward pivotal movement of the prop. The spool-like roller carried thereby will roll downwardly along the track which causes upward movement of the conveyor as shown in Fig. 2. When the discharge end of the elevator is at the desired elevation the handle 89 of the crank 88 is re-engaged with the hook 90 to retain the elevator in adjusted position.

When it is desired to lower the elevator upon completion of the job, the handle is disengaged from the hook and the crank turned in the opposite direction to pay out the cable so that the tubular housing of the elevator returns to its engagement with the seat 68, after which the clamp 69 is applied to permit transportation of the elevator to another job site.

If desired, the auger extension 44 may be connected with the projecting end of the shaft 12 through the universal joint 43 and the auger extension laid on a pile of material so as to move the material toward the inlet of the main auger. In this way the entire pile may be moved without shifting the elevator or without shoveling of the material onto the exposed end of the screw.

From the foregoing it is obvious that I have provided an elevator of the auger type that is of simple construction and which is readily

be used. If a longer length elevator is required, additional sections may be connected between the flanges 5 and 6 with the added auger sections which are rotatably mounted in the tubular housing sections.

What I claim and desire to secure by Letters Patent is:

1. An elevator including an elongated tubular casing having an inlet at one end and an outlet at the other, an auger rotatable in the casing for moving material from the inlet to the outlet, a supporting frame including side members located below the casing and converging toward said inlet end, brackets on the converging ends of said side members, means for pivotally connecting the inlet end of the casing with said brackets, a single pair of wheels journalled on the frame at the opposite ends of the side members whereby the frame is supported and adapted to rock on the axis of the wheels when the inlet end of the casing is supported on a pile of material and is adapted to move downwardly as the material is removed by the auger when the elevator is in use, a motor carried on the frame at the wheel supported end, a drive shaft rotatably supported on the frame and having an end spaced to one side of one of said brackets, a driving connection between the shaft and the motor, a shaft extension having an end spaced from said end of the drive shaft, a driving connection between the shaft extension and the auger at said inlet end of the casing, a universal joint connecting said spaced ends of said shafts in lateral registry with said pivotally connecting means, and means adjustably supporting the outlet end of the casing from the supporting frame at different angles with respect to the side members of the supporting frame.

2. An elevator including an elongated tubular casing having an inlet at one end and an outlet at the other, an auger rotatable in the casing for moving material from the inlet to the outlet, a supporting frame including side members located below the casing and converging toward said inlet end, brackets on the converging ends of said side members, means for pivotally connecting the inlet end of the casing with said brackets, a single pair of wheels journalled on the frame at the opposite ends of the side members whereby the frame is supported and adapted to rock on the axis of the wheels when the inlet end of the casing is supported on a pile of material and is adapted to move downwardly as the material is removed by the auger when the elevator is in use, a motor carried on the frame at the wheel supported end, a drive shaft rotatably supported on the frame and having an end spaced to one side of one of said brackets, a driving connection between the shaft and the motor, a shaft extension having an end spaced from said end of the

drive shaft, a driving connection between the shaft extension and the auger at said inlet end of the casing, a universal joint connecting said spaced ends of the shafts in lateral registry with said pivotally connecting means, means adjustably supporting the outlet end of the casing from the supporting frame at different angles with respect to the side members of the supporting frame, an auger extension, and means connecting the auger extension with the driving connection between the auger and the shaft extension to operate the auger extension.

3. An elevator including an elongated tubular casing having an inlet at one end and an outlet at the other, an auger rotatable in the casing for moving material from the inlet to the outlet, a supporting frame below the casing, brackets on the frame at the inlet end of the casing, means for pivotally connecting the inlet end of the casing with said brackets, a single pair of wheels journalled on the opposite sides of the frame at the opposite end whereby the casing and frame are adapted to rock on the axis of the wheels when the inlet end of the casing is supported on a pile of material and is adapted to move downwardly as the material is removed by the auger when the elevator is in use, a motor carried on the frame at the wheel supported end, a drive shaft rotatably supported on the frame and having an end spaced to one side of one of said brackets, a driving connection between the shaft and the motor, a shaft extension having an end spaced from said end of the drive shaft, a driving connection between the shaft extension and the auger at said spaced ends of the inlet end of the casing, a universal joint connecting said shafts in lateral registry with said pivotally connecting means, and means adjustably supporting the outlet end of the casing from the supporting frame at different angles with respect to the side members of the supporting frame.
